UNITED STATES PATENT OFFICE.

OSCAR B. HANSON, OF DICKINSON, NORTH DAKOTA.

COLLAPSIBLE CASE.

Application filed March 10, 1927. Serial No. 174,362.

This invention relates to packing and storage receptacles and pertains particularly to a knock-down box or crate.

The primary object of this invention is to provide, in a manner as hereinafter set forth, a box, or crate, which may be easily and quickly completely disassembled so that the sides, end walls and partitions or the central parts thereof may be stacked one upon the other and secured together for shipment.

This invention contemplates briefly the provision of a receptacle having top, bottom and side walls, and end walls, each of the end walls carrying a plurality of angled plate members mounted thereon in such manner that one of the flanges of each of the members will overlie an adjacent edge of a side wall while the other flange which is provided with a pair of arcuate slots is secured to the face of the end wall by appropriate headed members which extend through the arcuate slots. By moving the plates in one direction they ride upon the members which secure them to the face of the end wall causing the other flange to move away from the edge of the wall so that one of the side wall members of the box may be placed in position or removed from position against the adjacent edge of the end wall. A central partition member is provided which has upon its edges a plurality of studs or pins designed to engage in adjacent key-hole slots formed transversely of the central portion of each of the side walls.

A further and final object of the invention is to provide, in a manner as hereinafter set forth, a collapsible crate or box which will be strong and durable, easily set up, or taken apart, and comparatively inexpensive to manufacture.

Other objects and advantages of the invention will become apparent as the description of the same proceeds, and the invention will be best understood from a consideration of the following detailed description taken in connection with the accompanying drawings forming a part of this specification, with the understanding however, that the invention is not confined to any strict conformity with the showing of the drawings but may be changed or modified so long as such changes or modifications mark no material departure from the salient features of the invention as expressed in the appended claims.

In the drawings:

Figure 1 is an end elevation of the box embodying this invention,

Figure 2 is a side elevation of the same,

Figure 3 is a section taken upon the line 3—3 of Figure 1.

Figure 4 is a section taken upon the line 4—4 of Figure 2.

Figure 5 is a transverse section taken upon the line 5—5 of Figure 4.

Figure 6 is a transverse section taken upon the line 6—6 of Figure 4.

Figure 7 is an enlarged detailed perspective view of one corner of the box.

Figure 8 is a detailed perspective view of the central partition of the box.

Figure 9 is a perspective of one side wall of the box structure.

Figure 10 shows in end elevation one corner of the box showing the manner in which the securing plate is shifted for the release or insertion of a side wall.

Figure 11 is an enlarged sectional view taken through and longitudinally of one of the securing plates showing the manner in which the same is secured to the end wall of the box.

Figure 12 is a section taken longitudinally of one of a reinforcing plate extending transversely of the central portion of one of the side walls.

Referring now to the drawings in detail wherein like numerals of reference indicate corresponding parts throughout the several views, the box structure or crate embodying this invention comprises four side wall members 1, 2, 3 and 4, a pair of end walls 5 and 6, and a central partition wall 7.

Each of the side walls has extending transversely of the central portion thereof, a reinforcing plate 8 through each of which a plurality of key-hole slots 9 are formed which slots extend through the adjacent walls.

As crates of the character are usually constructed of wood, a reinforcing body is secured over each end edge of each side wall, as indicated at 10.

Each of the end walls 5 and 6 has secured to the outer face thereof adjacent each side edge, a pair of angled side wall securing plates each indicated generally by the numeral 11.

Each of the side wall retaining members 11 comprises a pair of flanges 12 and 13 arranged in right-angular relation as is clearly shown in the several views of the drawings, the

flanges 12 being arranged against the outer face of the wall in such manner as to cause the attached flange 13 to project over the adjacent edge of the wall. Each side edge of each end wall is provided with a pair of these angled retaining plates 11 and the opposed ends of the flanges 12 of each pair, are provided with a rolled finger hold 14 while secured to the outer face of the walls between the opposed ends of each pair of members 11, is an arcuate spring member 15 secured to the outer side of the end wall by a pin or screw member 16 which passes through the central portion thereof and secures the member 15 with the ends directed downwardly against the supporting wall body. When the side wall securing plate members 11 are drawn together, the portions 12 ride up upon the adjacent end of the spring member 15 as will be hereinafter described.

The flanges 12 of each of the angled securing plates 11 are provided with a pair of arcuate slots 17 which slots extend from the inner or free edge of the plate in which they are formed toward that end upon which the finger hold 14 is formed. Extending through each of the slots 17 of each member 11 is a securing pin or groove 18 upon which the member rides. From the foregoing description it will be readily seen that when the opposed ends of each pair of side wall securing plates are drawn inwardly together they will be caused to move in such manner as to shift the flange portions 13 outwardly away from the adjacent edge of the end wall, and the inner end of each of the members will ride upon the spring member 15. When the members 11 are returned to their position the locking spring 14 will bear against the inner ends of the members and maintain them in operative position.

The central partition 7 of the crate has each side edge provided with a plurality of headed pin members 19 which correspond in number to the key-hole slots 9 of an adjacent one of the side walls of the box and when the box is being assembled the partition 7 has a side wall secured to each side edge thereof by the extension of the members 19 through the key-hole slots formed therein, the wall being secured to the partition by moving it in such manner as to engage the heads of the members 19 over the constricted portions of the key-hole slot as will be readily understood.

When the box is being assembled all of the retaining plate members 11 are moved to the releasing position or in other words each pair of members is drawn together to cause the flange portions 13 to move outwardly from the adjacent edge of the end wall carrying the members. Three of the side walls can be fixed to the partition members 7 in the manner described and then the

end walls may be placed in position to cause the flange portions 13 of the members 11 to overlie one end of each of the side walls. Each pair of retaining members 11 overlying each of the said side walls may then be shifted to locking position and the flange portions 13 will bear against and frictionally hold the walls in contact with the adjacent edges of the end walls. After filling the crate, the top wall can be slipped in position beneath the raised members 11 at each end of the open side of the box and after the members 19 have engaged in the key-hole slots 9 of the top then the members may be shifted to locking position in the manner described. 70 75 80

From the foregoing, it will be readily seen that the box embodying this invention may be easily and quickly set up or taken down and may be used any number of times for shipping eggs or other material as the emptied crates can be folded and secured together before returned to the shipper. 85

Having thus described my invention, what I claim is:

1. A knock down box of the character set forth comprising side and end wall members, said side walls having their ends extending across and positioned against the side edges of the end walls, angled securing plates overlying the abutting edges of the end walls and the adjacent side walls at each of the four sides of the box, that portion of each of the securing members lying against the end walls, having arcuate slots formed therein and retaining pin members extending through the arcuate slots of each of said securing members and engaging the adjacent end wall for maintaining the securing members in slidable engagement with their respective end wall members, said securing members when shifted in one direction being moved from contact with the adjacent side wall members and when shifted in the opposite direction, being moved to frictional engagement with the adjacent side wall members to secure the side and end walls together. 90 95 100 105 110

2. A knock down box of the character described, comprising side and end wall members, a pair of angled plate members at each side edge of each end wall, each member of each pair having one portion thereof arranged against the outer face of the adjacent end wall and provided with arcuate slots and the other portion thereof extending over the adjacent edge of the end wall to overlie the end of the adjacent side wall member, and securing elements extending through said slots into the adjacent end wall to slidably support the angled members thereon, said slots being so formed that when each pair of members is drawn together, the side overlying portions thereof will be raised from contact with the box side wall members, the reverse movement of the angled members caus- 115 120 125 130

ing the side overlying portions to clamp the side wall members to the edge of the adjacent end wall.

3. A knock down box of the character described, comprising side and end wall members, a pair of angled plate members at each side edge of each end wall, each member of each pair having one portion thereof arranged against the outer face of the adjacent end wall and provided with arcuate slots and the other portion thereof extending over the adjacent edge of the end wall to overlie the end of the adjacent side wall member, and securing elements extending through said slots into the adjacent end wall to slidably support the angled members thereon, said slots being so formed that when each pair of members is drawn together, the side overlying portions thereof will be raised from contact with the box side wall members, the reverse movement of the angled members causing the side overlying portions to clamp the side wall members to the edge of the adjacent end wall, thereto, and resilient retaining elements posi-

tioned between the opposed ends of each pair 25 of angled members and designed to normally maintain the angled members in side wall securing position.

4. A knock down box of the character described, comprising top, bottom, side and end 30 wall members, shiftable plate members carried by and having limited movement over a face of certain of said walls, and an engaging member carried by each plate for engagement over an adjacent wall to maintain the same 35 in position.

5. A knock down box of the character described, comprising side, top, bottom and end wall members, and angled locking plates positioned over the end edges of the box, each 40 of said plates having one flange thereof shiftably secured to a wall member, the secured flange of each plate being so attached as to cause the associate flange to move towards or away from the adjacent wall member when 45 the plate is shifted.

In testimony whereof I affix my signature.
OSCAR B. HANSON.
